Des. 1895

N. C. Whitecomb, of Oak Hill, N. Y.

Letters Patent No. 1895-Dated Feby 27th 1895.

Design for a metal Pulley Block.

***

The schedule referred to in these Letters Patent and making part of the same.

****

To all whom it may concern:

Be it known that I, N. C. Whitecomb, of Oak Hill, in the County of Greene, and State of New York, have invented or produced a new and original Design for a Cast Metal Pulley Block; and I do hereby declare that the following is a full, clear and exact description of the same, reference being had to the accompanying drawings, making a part of this specification, in which -

Figure 1. is a side view of a cast metal pulley block constructed according to my design.

Figure 2. an end view of the same.

Similar letters of reference indicate corresponding parts in the two figures.

This invention relates to the shape of the frame in which the sheave or pulley is fitted. This frame is composed of a segment a, which is over the upper part of the sheave or pulley, b, and is connected to the axle, c, of the sheave or pulley by two curved arms d, d, at each side of the latter. The shape of these arms is shown clearly in Figure 1.

The segment, a, is scooped or hollowed out at each end as shown at, e, in Figure 2, and from the lower ends of the arms d, d, at each side of the sheave or pulley, b, there is a dependent arm f, the lower ends of which are connected by a rod, g, see Figure 2.

At the centre of the upper part of the segment a, there is a conical projection, h, having a slightly concave exterior, said projection serving as a base for the ring, i, of the pulley block. The sheave or pulley, b, may be of the usual form and does not form any part of the design.

Having thus described my invention, what I claim as new and desire to secure by Letters Patent is,

The configuration of the parts as herein shown and described to form a new and original design for a cast metal pulley block.
